US00D451393B1

(12) **United States Design Patent** (10) **Patent No.:** **US D451,393 S**
Gerhart et al. (45) **Date of Patent:** **** Dec. 4, 2001**

(54) **VENT CLOSURE**

(75) Inventors: **Mark Douglas Gerhart**, Westminster, MD (US); **Edward John Giblin**, Hopatcong, NJ (US); **Eugene Francis Haffner**, Waterville, OH (US); **George Richard Trepina**, Holland, OH (US); **Carlton Roy Mousseau**, Sylvania, OH (US)

(73) Assignee: **Unilever Home & Personal Care USA, division of Conopco, Inc.**, Greenwich, CT (US)

(**) Term: **14 Years**

(21) Appl. No.: **29/107,638**

(22) Filed: **Jul. 9, 1999**

(51) LOC (7) Cl. **09-07**

(52) U.S. Cl. **D9/453**

(58) Field of Search D7/392.1, 510, D7/511; D9/300, 337, 434, 435, 440, 445, 447, 448, 449, 451, 452, 453, 516, 524, 525, 547; 222/518, 519, 559, 562, 111, 153.1, 153.14; 220/288, 726; 215/228, 230

(57) **CLAIM**

The ornamental design for a vent closure, substantially as shown and described.

DESCRIPTION

FIG. 1 is a top and side perspective view of a vent closure with a container shown in dotted lines for environmental purposes only and forming no part of the claimed design; FIG. 2 is a top plan view of the vent closure; and, FIG. 3 is a side view thereof, it being understood that all side views thereof are identical thereto.
